2,011,290

DYNATRON OSCILLATOR

Paul O. Farnham, Boonton, N. J., assignor, by
mesne assignments, to Radio Corporation of
America, New York, N. Y., a corporation of
Delaware

Application June 15, 1932, Serial No. 617,446

19 Claims. (Cl. 250—36)

This invention relates to dynatron oscillators and particularly to methods of and circuit arrangements that are well adapted for tuned and/or for modulated dynatron oscillators.

5 The magnitude of the output voltage of a dynatron oscillator, for constant control grid bias, will vary with the load impedance and, in oscillators having a plate circuit tunable over a frequency band, the output is usually far from constant at all frequencies. When the output is modulated by a low frequency voltage impressed in the control grid circuit, the percentage of harmonics present in the output circuit of the known dynatron oscillators varies materially with the tuning.

10 Objects of this invention are to provide methods of and circuit arrangements for maintaining the output voltage of a dynatron oscillator substantially independent for wide variations of the plate load impedance, and for reducing the production of harmonic frequencies in modulated dynatron oscillators. Further objects are to provide methods of and circuit arrangements for automatically varying the control grid bias of a tuned dynatron oscillator as a function of the amplitude of oscillation and at such rate as to provide a predetermined relation between the output voltage and the oscillating frequency. More specifically, an object is to provide a tuned dynatron oscillator circuit including a rectifier for automatically developing a direct current grid bias potential by rectification of the oscillatory voltage developed in the output circuit of the oscillator.

15 These and other objects and advantages of the invention will be apparent from the following specification in which:

20 Fig. 1 is a curve sheet showing the relationship between the dynatron output voltage and control grid bias for different values of the plate load impedance;

25 Figs. 2, 3, 4 and 5 are circuit diagrams of dynatron oscillators embodying the invention.

30 In the curve sheet, Fig. 1, the curves A, B and C will be recognized as typical curves illustrating the relationship between the peak oscillating voltage of a dynatron and the direct current control grid bias, the several curves being obtained for different values of the plate load impedance, R_B , of the oscillator. The tuned circuit of an oscillator designed for operation over a frequency band is usually the plate impedance and, in the case of the usual tuned circuit, the impedance of this load varies with the tuning. In Fig. 1, the three curves represent the voltage-grid bias relationship for different frequencies, i. e., curve A corresponds to a low frequency or relatively low load impedance,

35 curve B corresponds to a higher frequency or a higher load impedance, while curve C corresponds to a high frequency or relatively high load impedance.

40 According to the known methods of operating the dynatron oscillator, a fixed negative bias has been provided by a cathode resistor or by a separate source of bias voltage. With a cathode resistor, the direct current bias on the grid does not vary with the output voltage but is dependent 45 only upon the plate and screen grid potentials.

45 For a fixed negative bias of the value indicated by OF, the operating point P would be favorably located when the circuit is tuned to the frequency corresponding to curve B. As the oscillator is 50 tuned to higher or to lower frequencies, the operating point will not be located at the center of the approximately linear portion of the characteristic curve. For the higher frequency of curve A, the operating point P₁ will fall on the lower curved 55 section of the characteristic, and for the lower frequency, curve C, the operating point P₂ will fall at the upper bend of the curve. These curves therefore explain the difficulties which have been experienced in designing dynatron oscillators for 60 operation over a band of frequencies, since a fixed bias that is appropriate for a high voltage output at one frequency will result in a lowered output for other frequencies.

65 In accordance with the present invention, the control grid bias is automatically varied as a function of the output voltage, the change in bias voltage being in such sense and at such a rate as to maintain an approximately constant output voltage.

70 As shown in Fig. 2, the dynatron oscillator includes a tetrode 1 having a tuned plate circuit LC and the voltages impressed upon the plate P and screen grid G₂ from the sources indicated by E_B and E_D, respectively, are such that the tube has a negative plate resistance. The control grid G₁ is connected to the cathode through a resistance R which is by-passed by a condenser C₁.

75 The resistance R forms the output circuit of a diode rectifier 2 which has an input circuit comprising an inductance L₁ that is coupled to the plate inductance L.

80 It will be apparent that the oscillating voltage E of the tuned plate circuit LC establishes a voltage E₂ across the inductance L₁ and that, due to the diode rectifier action, a direct current voltage is developed across the resistance R. The bias voltage across the resistor R varies as a substantially linear function of the peak oscillating voltage E and is represented, in Fig. 1, by the straight 85

line OD, the slope of the line OD being approximately unity, using the scale of oscillator voltage marked E_2 .

The voltage ratio, E_2/E , may be so chosen that 5 the operating point P falls at the center of the linear portion of curve B, as in the case of a fixed bias OF. If the circuit shown in Fig. 1 is tuned to other frequencies, the operating point will not move along the ordinate PF, as in the prior circuits employing a fixed bias, but will move along 10 the line OD. The variation of output voltage with tuning is therefore much less than that which was observed with the known oscillator circuits.

The control grid bias voltage of the Fig. 2 circuit falls to zero when the tube is not oscillating 15 since the bias voltage is derived solely from rectification of a voltage developed in the output circuit. As shown in Fig. 3, a fixed bias voltage E_c may be impressed on the grid to insure a substantially negative bias over the entire operating 20 range of the oscillator. This bias may be provided by a battery or other current source 3 which is so connected between the grid G_1 and the resistance R that a positive bias is impressed on 25 the grid when the output voltage E falls to zero. To obtain relatively large changes in the current flow through rectifier 2 for small changes in the value of the output voltage E, the inductances L_1 may include a larger number of turns than the 30 plate inductance L. The voltage E_2 on the rectifier may thus be made much greater than the voltage E.

The operation of the Fig. 3 circuit is indicated by the line HIJ which has a slope determined by 35 a different scale for the ordinate E_2 and is drawn through the zero ordinate at a point representing, on the same voltage scale as the voltage E_2 , the fixed bias E_c . By appropriate choice of the step-up ratio of the transformer L, L_1 , and the bias E_c , 40 this line will intersect the curve B at the desired operating point P. With the Fig. 3 circuit, the operating point P will move along the line HI when the oscillator is tuned over its frequency band. It will be noted that such operation is to 45 be preferred to that of the Fig. 2 circuit, since the line H passes approximately through the centers of the linear sections of the several curves. Another circuit for holding the locus of the operating point P to a line such as the line HI is shown 50 in Fig. 4, in which the rectifier circuit includes a source of bias voltage, such as a battery 4, for impressing a negative potential on the rectifier plate P_1 . The diode will not pass a rectified current until the peak voltage E_2 exceeds the delay 55 action bias voltage E_k that is introduced by the battery 4. The effect of this delay action is to reduce the control grid bias to zero when the peak voltage E_2 on the rectifier decreases to and below the value of the diode bias voltage E_k . In Fig. 1, 60 the line OIH indicates the relationship between the control grid bias and the peak oscillating voltages E, E_2 .

An examination of Figs. 2 and 3 will show that the cathodes of the dynatron and of the rectifier 65 are at the same potential. It is therefore possible to combine these two tubes in a single envelope. Such an arrangement as applied to the Fig. 4 circuit is shown in the modulated oscillator circuit of Fig. 5.

70 In addition to the usual tetrode elements, the tube 1' includes an auxiliary plate P_1 adjacent to the cathode. As compared with the Fig. 4 circuit, the battery 4' for applying the delay action bias to the diode is connected between the input inductance L_1 and the output resistance R. This

location of the battery 4' provides the desired bias on the plate P_1 but does not establish a fixed bias between the cathode and the control grid G_1 of the dynatron. The secondary winding of an 5 audio frequency transformer 5 is connected between the control grid G_1 and that terminal of the resistance R which joins the battery 4'. A microphone 6 is included in the primary circuit of the transformer 5.

An audiofrequency by-pass condenser C_2 is 10 shunted across the battery 4' and the resistance R. In the circuits described above, the by-pass condenser may be comparatively small as its only function is to prevent the development of a 15 signal frequency voltage across the bias resistor R. In the modulated oscillator, however, the by-pass must have such low impedance for the modulation voltage that the direct current bias does not vary with the modulation voltage. The peaks of 20 the modulation voltage will vary the instantaneous voltage between G_1 and cathode but the large condenser C_2 will render the rectifier output substantially independent of these fluctuations of the oscillating voltage.

It is possible, of course, to employ a modulation voltage E_m of such magnitude that the instantaneous voltage swings are carried to or past the bends of the characteristic curve but, in general, the modulation voltage will be of such magnitude that the operation takes place entirely upon the linear portion of the characteristic when the operating point is located approximately at the center of that linear portion.

While the described circuits indicate the general 35 methods which are contemplated by the present invention, it will be apparent, to those familiar with the design and construction of oscillators, that the same method of operation may be obtained with other circuit arrangements. Manual 40 controls may be provided for adjusting the magnitude of the voltage ratio E_2/E or for adjusting the relatively fixed bias voltages, thus providing for flexibility in the control or adjustment of the oscillator. The rectifier output may, if desired, 45 be amplified to increase the sensitivity of the bias variation with changes in the amplitude of the oscillating voltage.

These and other changes which may be made in the choice and the relationships of the circuit elements fall within the spirit of my invention as 50 set forth in the following claims.

I claim:

1. In the operation of a dynatron oscillator having a cathode, a control grid and at least two other electrodes; a tuned circuit connected between one of said other electrodes and the cathode; and means impressing on said other electrodes steady potentials which are both positive with respect to the cathode and of relative values resulting in the production of dynatron oscillations; the process which comprises rectifying a component of the oscillatory current to obtain a direct current voltage that varies with the oscillating voltage, and impressing said direct current voltage on the dynatron as a control grid bias.

2. The process as set forth in claim 1, wherein the direct current bias voltage is varied with but at a more rapid rate than changes in the peak 70 oscillating voltage.

3. The process as set forth in claim 1, wherein a positive control grid bias is initially applied, and the rectified voltage is negative and increases in a negative sense with the oscillating voltage, 75

whereby the net bias falls to zero before the oscillating voltage becomes zero.

4. A self-oscillating dynatron system comprising the combination with a tube having a cathode cooperating with a control grid and at least two other elements, a resonant circuit connected between the cathode and the outer one of said elements for tuning said oscillator over a frequency range, and means impressing on said other elements steady potentials which are both positive with respect to said cathode and of relative values which result in self-oscillation, of means actuated by the oscillating voltage to vary the control grid bias automatically with changes in the amplitude of the oscillating voltage.

5. A self-oscillating dynatron as claimed in claim 4, wherein said bias-varying means includes a rectifier.

6. A dynatron oscillator comprising a dynatron tube having a cathode, a control grid and two other electrodes, a resonant circuit for tuning the dynatron over a frequency range, said tuned circuit being connected between the cathode and one of said other electrodes, a control grid circuit including a resistance, means impressing on said other electrodes steady potentials which are both positive with respect to the cathode and of relative values producing dynatron oscillations, and means for developing across said resistance a direct current voltage that varies as a function of the amplitude of the oscillating voltage.

7. A dynatron oscillator as set forth in claim 6, wherein said means includes a diode rectifier having an input circuit coupled to said resonant circuit, the said resistance being included in the output circuit of said diode rectifier.

8. An oscillator comprising a tube having a cathode cooperating with a control grid and at least two other electrodes, a tuned oscillatory circuit between one of said other electrodes and the cathode, means impressing between the said other electrodes and the cathode direct current potentials resulting in the generation of an oscillatory voltage across said tuned circuit, a resistance between control grid and cathode, means for maintaining said control grid at the same oscillatory potential as said cathode, means including a rectifier for developing across said resistance a direct current voltage that varies automatically with the amplitude of the oscillatory voltage, thereby to impress on the control grid a negative bias that becomes more negative with increases in the amplitude of the oscillatory voltage, and means for reducing the bias voltage to zero before the oscillatory voltage falls to zero.

9. The invention as set forth in claim 8, wherein said last means comprises a source of direct current applying a fixed positive bias on the control grid.

10. The invention as set forth in claim 8, wherein said last means comprises means for rendering said rectifier inoperative for peak oscillating voltages of less than a predetermined value.

11. In a dynatron oscillator, the combination with a tube having a cathode, control grid, a second grid and plate; of a tuned plate circuit, a control grid circuit including a resistance, means for impressing on said second grid and plate steady potentials which are both positive with respect to said cathode and of relative values resulting in the production of dynatron oscillations, and a diode having an input circuit coupled to said tuned plate circuit, said resistance comprising the output circuit of said diode.

12. The invention as set forth in claim 11, wherein said diode comprises the cathode of said tube and an auxiliary plate element associated therewith.

13. The invention as set forth in claim 11, in combination with means in said control grid circuit for modulating the oscillating voltage developed across said tuned plate circuit.

14. A dynatron oscillator comprising a vacuum tube having cathode, control grid, screen grid, 10 and plate elements, a resonant circuit coupled to said plate and cathode, a source of potential maintaining the screen grid at a higher positive potential than the plate with respect to the cathode, a resistance in circuit between said control grid and said cathode, means suppressing the development of oscillator frequency voltage between control grid and cathode, and means for impressing on the control grid a negative bias that becomes more negative with increases in the 20 amplitude of the oscillatory voltages; said means including a rectifier having input means for impressing thereon a voltage which varies with the oscillatory voltage, and means for passing the output current of said rectifier through said 25 resistance.

15. In the operation of an oscillator of the type including a vacuum tube having a cathode, a plurality of cold electrodes, circuit elements cooperating with said cathode and cold electrodes to constitute an oscillatory network, a grid electrode, and means preventing the development of oscillatory voltages between said grid electrode and cathode, the method of controlling the amplitude of oscillation which comprises rectifying 30 oscillating energy developed in said network, and applying between the cathode and grid the voltage resulting from such rectification.

16. An oscillation generator comprising an electron discharge device having an electron emitting cathode, an anode, a screen grid, and a control grid, and means for causing the emission of secondary electrons from said anode, resonant means in circuit with the electrodes of said device for controlling the frequency of oscillations generated thereby, and means actuated in dependence upon the oscillatory output from said device for applying a controlling bias potential to the control grid of said device whereby the amount of negative resistance exhibited by said device is 45 automatically controlled in a direction to produce 50 substantial constancy of output.

17. The method of stabilizing an electron discharge device oscillator whose circuit includes an electron emitting cathode, an anode, a screen 55 grid electrode, and an electron controlling member intermediate said cathode and screen grid, and means for causing an emission of secondary electrons from said anode which comprises rectifying the oscillations obtained from said anode 60 in excess of a predetermined value and utilizing the rectified oscillations for applying a bias potential to said electron controlling member thereby varying the number of primary electrons 65 which may reach said anode with any given potential supplied thereto and the number of secondary electrons which will be effectively emitted therefrom.

18. In combination, a negative resistance device comprising an electron discharge device 70 having a cathode, anode, control grid, and screen grid electrode, resonant means in circuit with the anode circuit of said device for controlling the frequency generated thereby, means for applying to the anode and screen electrodes of said 75

device operating potentials of such value that said valve operates over the downwardly sloping portion of its anode-voltage-electron current to anode characteristic, the arrangement being such that the negative conductance of the anode circuit of said valve is greater in magnitude than the dynamic conductance of the external circuit, whereby said device operates as a dynatron oscil-

lator, means for rectifying oscillatory current derived from the output circuit of said valve and means for applying as bias potential components to the control grid of said device potentials derived from the rectified oscillatory current.

19. An oscillator as claimed in claim 18, and in which said rectifying means includes a diode.

PAUL O. FARNHAM.
